Specification for Design.

Patented July 20, 1920.

Application filed November 20, 1919. Serial No. 339,446. Term of patent 3½ years.

To all whom it may concern:

Be it known that I, WILLIAM F. ROEHLLEN, a citizen of the United States, residing at Rochester, in the county of Monroe and State of New York, have invented a new, original, and ornamental Design for Embossed Wall-Paper, of which the following is a specification, reference being had to the accompanying drawing, forming a part thereof.

The figure is a section of embossed wall-paper, showing my new design.

I claim:

The ornamental design for embossed wall-paper as shown.

In testimony whereof I have hereunto set my hand, this 17 day of November, 1919.

WILLIAM F. ROEHLLEN.
